UNITED STATES PATENT OFFICE.

AXEL JOHNSON, OF OAKLAND, CALIFORNIA, ASSIGNOR TO AMERICAN CAN COMPANY,
OF SAN FRANCISCO, CALIFORNIA, A CORPORATION OF NEW JERSEY.

APPARATUS FOR CUTTING AND APPLYING RING-LINERS TO THE FLANGE OF CAN ENDS.

1,162,169.

Specification of Letters Patent. Patented Nov. 30, 1915.

Application filed October 21, 1914. Serial No. 867,812.

To all whom it may concern:

Be it known that I, AXEL JOHNSON, a citizen of the United States, residing at Oakland, in the county of Alameda and State of California, have invented certain new and useful Improvements in Apparatus for Cutting and Applying Ring-Liners to the Flange of Can Ends, of which the following is a specification.

The hereinafter described invention relates to an apparatus for cutting ring liners from a fibrous web or blank and applying the ring liner so cut to the flange of a positioned can end, and the same comprises co-acting instrumentalities for feeding a web or blank to cutting position, severing the ring liner therefrom, carrying the ring liner so cut to a station for receiving a can end, feeding and positioning a can end relative to the cut ring liner, applying the cut ring liner to the flange of the positioned can end, and finally discharging the lined can end from within the machine, the various interconnected or associated working instrumentalities being automatic in their operations and the operation of the respective working elements being so arranged and timed relative to each other as to come in action at the proper time for carrying out successively the various steps incident to the cutting of the ring liner, and applying the same to the flange of a positioned can end.

The object of the invention is the production of a simple, efficient and durable machine for the carrying out of the work required, and one wherein the ring liner is cut from the fibrous blank on a single stroke of the cutting punch and the working of the associated instrumentalities is entirely automatic.

In the present case, the fibrous blank from which the ring liners are to be cut is illustrated as an endless web, intermittently fed beneath the cutting punch and while preference is given to the employment of an endless web as the fibrous blank from which the ring liner is to be cut, still, such is an immaterial feature of the invention, and I do not wish to be understood as limiting or confining the invention to such a form of fibrous blank, being well aware that a disk or other form of fibrous blanks may be utilized in

the machine for the cutting of ring liners therefrom.

To comprehend the invention, reference should be had to the accompanying sheets of drawings, wherein—

Figure 1 is a perspective view of the machine with certain parts removed and other parts broken away for clearness of illustration as to the construction. Fig. 2 is a top plan view of the machine, the supporting means for the endless web of fibrous material from which the ring liners are cut being removed. Fig. 3 is a transverse vertical sectional view taken on line $x-x$ —Fig. 2 of the drawings, and viewed in the direction of arrows a , and illustrating the rotatable turret, and the parts thereon, the means for imparting step or intermittent rotation to the said turret, the feed mechanism for the fibrous web, the cam disk for actuating the reciprocating devices controlling the movement of the die plunger, the action of the feed mechanism for the can ends or heads, and the devices for regulating the infeed of the endless web, said cam disk being partly broken away to illustrate the cam grooves therein. Fig. 4 is a vertical sectional view taken on line $y-y$ —Fig. 2 of the drawings, and viewed in the direction of arrows b , said section being through the rotatable turret and the end feed for supplying ends or heads to position within the rotatable turret. Fig. 5 is a vertical sectional view taken on line $r-r$ —Fig. 3 of the drawings, and viewed in the direction of the arrows thereon, certain parts of the machine being shown in full and other parts removed, said view illustrating the rotatable turret, and the cam disk for actuating the parts controlling the movement of the die punch, the can end feed and for placing the cut ring liner onto the flange of a positioned can end, and disclosing the driven shafts with the parts positioned thereon. Fig. 6 is a sectional plan view taken on the irregular line $s-s$ —Fig. 5 of the drawings, and viewed in the direction of the arrows, said view illustrating the Geneva mechanism for imparting step or intermittent rotation to the shaft carrying the horizontally rotatable turret. Fig. 7 is a vertical sectional view taken through the die punch, turret and

composite cutting die, and illustrating the paper web between the die punch and the composite die for the cutting of a die ring therefrom. Fig. 8 is a similar view illustrating the die punch in its lowered position and the ring liner cut from the endless web and held between the die punch and the composite cutting die. Fig. 9 is a similar view taken through the turret, the composite die and the can end feed, illustrating a can end positioned in the turret relative to the cut ring liner. Fig. 10 is a similar view taken on line $w-w$ —Fig. 2 of the drawings and viewed in the direction of the arrows c , said view illustrating the assembling means for the cut ring liner and the can end in raised position, the ejector device lifted thereby and the cut ring liner moved from between the recess of the composite die onto the flange of the can end, and the presser plate for holding the can end in position during the placing of the said ring liner. Fig. 11 is a broken plan sectional view taken on the irregular sectional line $z-z$ —Fig. 9 of the drawings and viewed in the direction of the arrows.

In the drawings, reference being had more particularly to Figs. 1 and 5 thereof—the letter A is used to designate any suitable form of a frame capable of sustaining the working parts of the apparatus and which frame in the present case comprises an upper platform 1 and a base plate 2, held in spaced horizontal relation by means of a suitably constructed connecting piece 3. Within the said frame structure there is mounted in suitable bearings a vertical shaft 4, to which rotary motion is imparted by the gear wheel 5 thereon meshing with a pinion 6 on a longitudinally disposed drive shaft 7, which shaft receives its motion from a source of drive power in any suitable manner, as, for instance, by a power belt working over a belt pulley 8 secured to the said shaft 7.

On the shaft 4 there is keyed beneath the platform 1 a hub 9, provided with an outwardly projected arm 9' carrying a roll 9², which roll during the rotary movement of the said arm 9' moves into and out of the radial slots 10 of the Geneva wheel 10^a for imparting a step or intermittent rotation to the shaft 11 from the driven shaft 4 through the medium of the said Geneva wheel 10^a keyed to the said shaft 11, Fig. 6 of the drawings.

The vertical shaft 11 works within suitable bearings of the platform 1 and the base plate 2, and the upper end thereof projects a slight distance above the said platform 1 and has secured thereto the horizontally disposed rotatable turret 12, which turret is provided circumferentially with a plurality of spaced vertically disposed openings 13, each of which openings has rigidly secured therein a composite cutting die composed of

the spaced concentric cutting die rings 14 and 14', Figs. 7, 8, 9 and 10 of the drawings. Immediately above the turret 12 and held in spaced relation thereto by a spacing block or collar 15 is located a horizontally disposed disk 15', which said disk is provided circumferentially with a plurality of spaced vertically disposed openings 16 held in registry with the vertical openings 13 of the turret 12. The said disk 15' together with its spacing block or collar 15 is secured to the shaft 11 so as to revolve therewith and in unison with the turret 12, and the circumferential clearance space 17 between the said disk 15' and the upper surface of the turret 12 provides a passage-way for the free feed of the hereinafter described web from which the ring liners are cut. (Figs. 1, 3 and 5 of the drawings.)

To one side of the frame of the machine and projecting vertically therefrom is secured a bracket 18, Figs. 1, 2 and 5 of the drawings, the inwardly projected overhanging portion 18' of said bracket is provided with the vertical grooves or guide-ways 19, in which the vertically movable cross-head 20 carrying the die punch 21 works. The said die punch 21 is so positioned relative to the rotatable turret 12, that with each rest or stop of the intermittent movement of the said turret, the die punch 21 will be in axial alinement with one of the composite cutting dies within the vertical openings 13 of the turret. The stem 22 of the die punch 21 is connected to the cross head 20, which cross-head in turn, through the medium of the toggles 23 and 23', is connected by the pin 24 to the link 25, pivoted to the upper end of a lever 26 fulcrumed to the bracket 18 and connected at its lower end to a slide 27—Fig. 5 of the drawings. The said slide 27 carries a depending roll 28, which roll works within a cam groove 29 cut in the upper face of the horizontally disposed cam disk 30, secured to and carried by the shaft 4. The working of the roll 28 within the cam groove 29 during the rotary movement of the cam disk 30 imparts a reciprocating motion to the slide 27, acting to throw the lever 26 and through the medium of the connecting link 25 and toggles 23 and 23' imparting vertical reciprocating motion to the cross-head 20 for raising and lowering the die punch 21 carried thereby, the movement of the said parts being so timed as to lower the die punch 21 when one of the vertical openings 13 of the intermittent movable turret is in axial alinement therewith. In the present case the vertically reciprocating die punch 21 is illustrated as positioned above the composite cutting die, but the positioning of these parts relative to each other is an immaterial feature, just so long as the die punch or punch ring 21 co-acts with the composite cutting die to cut on a single

stroke from a positioned web or blank a ring liner and leave the ring liner so cut positioned within the composite cutting die, in order that the said cut ring liner may be carried by the composite cutting die to a station for having a can end positioned relative thereto and the positioned end and cut ring liner then carried to an assembling station for having the ring liner removed from the composite cutting die and applied to the flange of the positioned can end.

While the die punch 21 is illustrated as a cutting ring attached to the stem 22 actuated by the reciprocating movement of the cross-head 20, and of slightly less diameter than that of the outer cutting ring 14 of the composite die so as to pass within the recess or clearing space a' between the concentric cutting rings 14 and 14', and preference is given to such a construction of the die punch—still, any suitably constructed form of a reciprocating die punch capable of co-acting with the composite cutting die for forcing the web or blank against the cutting edges of the said composite cutting die and severing therefrom the desired ring liner and leaving the same within the clearing space or recess a' of the composite cutting die, may be employed in the present machine.

In the present case, a paper web is utilized as the blank from which the ring liners are to be cut and for this purpose a bracket 31—Figs. 1 and 3 of the drawings—is secured to the frame of the machine, which bracket supports a horizontally disposed guide plate 31^a provided with a channel 31^b and within the bracket 31 is mounted a roll 32, on which is wound the paper web 32'. The free end portion of the web 32' works within the channel 31^b of the guide plate 31^a and is passed over the turret 12, within the circumferential clearance space 17 which exists between the disk 15' and the upper face of the turret 12, and on its inward or feed movement the said web passes between the die punch 21 and one of the composite cutting dies positioned beneath and in axial alinement with the said die punch. The paper web 32' is advanced or fed inwardly by means of the longitudinally reciprocating feed block 33, the under face of which is provided with a layer 33' of rubber or other suitable material for frictionally engaging with the upper face of the web 32'. The said block rests on the web 32' and is connected by a link 34 to a stud 34' laterally projected from the upper end portion of a lever 35, which said lever is fulcrumed at 36 to the bracket 31—Figs. 1 and 3 of the drawings. At its lower end the lever 35 is connected to the outer end of an actuating rod 37, which rod at its inner end is in turn connected to a longitudinally movable slide 38. This slide 38 carries an upwardly pro-

jected roll 39, which works within a cam groove 40 cut in the under face of the cam disk 30, so that during the rotary movement of the said disk the rod 37 through the slide 38 is actuated to throw the lever 35 to move the feed block 33 inwardly and outwardly relative to the center of the turret 12. On its inward stroke, owing to the angular disposition of the link 34, the said block 33 frictionally engages with the web 32' and advances or feeds the same inwardly a distance equal to the stroke of the said slide block; while on its outward movement or return stroke the slide block rides freely over the surface of the web 32', and during such movement of the slide block, owing to the disposition of the link 34, the same is held out of frictional contact with the web of paper. The action of the feed mechanism for the paper web or blank from which the ring liner is to be cut is so timed with respect to the intermittent movement of the turret 12 that an inward feed or travel of the web 32' takes place only at such time as an opening 13 of the turret is in axial alinement with the die punch 21.

With the web or blank positioned beneath the die punch and the turret 12 at its first rest position with one of its vertical openings 13 in axial alinement with the die punch, the said die punch 21, through the action of the previously described mechanism, descends onto the positioned web or blank 32', and moving within the die ring 14 by its shearing action cuts a circular or other shaped disk or blank therefrom, and continuing its downward movement forces the disk or blank so cut onto the cutting edge of the die ring 14' and by its shearing action cuts a ring liner a therefrom and carries the same into the annular recess or clearance space a' existing between the concentric die rings 14 and 14', Fig. 8 of the drawings. The cut out central piece b is forced within the die ring 14' by the presser head B carried by the stem 22 of the die punch 21, by reason of the upper portion of the cutting die 14' on the downward movement of the die punch entering within the annular recess or space a' existing between the outer wall of the presser head B and the inner wall of the die punch 21, which core pieces b accumulating within the die ring 14' are gradually forced from the lower open end thereof by the action of the die punch. On the return movement of the die punch, the cut ring liner is left within the annular recess or clearance space a' between the cutting rings 14 and 14' of the composite cutting die and so held is carried or moved by the step rotation of the turret 12 to the can end feed station.

At the can end feed station, there is secured to the frame of the machine a can end bracket plate 41 which extends over the

turret 12 and is provided with a vertical opening 41^a through which the can ends 42 singly discharge from the stack of can ends held within a suitable holder 43, upwardly projected from the bracket plate 41. In the under face of the said bracket plate 41 is provided a guide-way 44, in which works and reciprocates a shear plate 45, which slides beneath the stack of ends 42 within the holder 43 and cuts out the lowermost can end of the stack of ends 42. On the turret 12 being brought to a position of rest at the can end feed station with one of its vertical openings 13 in axial alignment with the outlet opening 41^a for the escape of the can ends, the lowermost can end 42 of the stack of ends contained within the holder 43, moves through the opening 16 of the disk 15 into the upper portion 20 of the opening 13, the edge of the can end flange resting on the cutting die ring 14, Fig. 9 of the drawings. When thus positioned, the shear plate or slide 45 is moved inwardly to cut out the lowermost positioned can end of the stack of ends, slightly raising and supporting the said stack for the time being. (Figs. 1 and 2 of the drawings.) The said shear plate or slide is moved inwardly beneath the stack of ends and 30 from beneath the same by means of the lever arm 46, connected at 47 to a rock-shaft 47' working in a bearing on the frame of the machine, Fig. 4 of the drawings. This arm 46 is pivoted at its upper end to the 35 under face of the shear plate or slide 45 and at its lower end is connected by the rock-shaft 47' to a crank-arm 47, which in turn is connected to an actuating rod 48. The actuating rod 48 at its inner end is 40 connected to a longitudinally movable slide plate 49, which like the slide plate 38, Fig. 3 of the drawings, is provided with an upwardly projected roll 50 working within a cam groove 51 cut in the under face of the 45 cam disk 30, the travel of the said roll 50 within the cam groove 51 operating the slide 49 and the rod 48 for imparting reciprocating motion to the lever arm 46 for moving the shear plate or slide 45 inwardly and 50 outwardly relative to the holder 43 for the stack of can ends 42.

At a point opposite to that of the fulcrumed lever 26 for actuating the reciprocating die punch 21, a link 52 connects the 55 slide 27 to a pin 53 on which pivot the toggles 54 and 55—Figs. 1 and 5 of the drawings. The shorter toggle member 54 is pivoted to a standard or bracket 56 upwardly projected from the frame of the 60 machine, while the companion toggle member 55 is connected at its upper end to a vertically movable slide block or member 57—Figs. 1, 5 and 10 of the drawings. The said slide block or member 57 works in guide- 65 ways 57' of the guide-head bracket 58, and at its upper end the slide block carries a cross-head 59, to which are pivotally attached two vertically extended spaced catches 60, which are connected one to the other and normally held inwardly pressed by the 70 tension of the spring 61. These catches lie within the circular line of travel or path of the spaced depending ejector rods 62 and engage with the flanged ends 63 thereof. Said ejector rods work through cut outs 64 75 formed in the circular flange 65 of the die ring 14', which flange rests on the upper edge of the retaining ring 66 screwed into the lower end of each vertical opening 13 of the turret 12—Figs. 1, 5, 9, 10 and 11 80 of the drawings. The said ejector rods or slides 62 work between the die rings 14 and 14' of the composite cutting die, and on the upward movement thereof force the cut ring liner *a* from within the annular recess 85 or clearance space *a'* between the said die rings onto the flange of the positioned can end 42—Fig. 10 of the drawings. During this upward movement of the slide block 57, the lower ends of the ejector rods 62 90 rest on the face of the cross-head 59, and are carried upwardly or raised thereby during the said movement of the slide block 57; and the upper ends thereof bearing against the cut ring liner *a* raise or eject the same 95 from within the clearance space *a'* and deposit the said ring liner onto the flange of the positioned can end 42—Fig. 10 of the drawings. The pressure applied to the flange of the can end during the action of 100 applying the cut ring liner thereto raises the can end from within the vertical opening 13 of the turret 12 and through the vertical opening 16 of the disk 15' until the upper surface thereof is brought into contact with the under surface of the presser plate 66' projected over the turret 12 and disk 15'—Fig. 2 of the drawings,—and which serves to hold the can end against further upward movement during the placing of the 110 ring liner to the flange thereof.

On the cut ring liner being applied to the flange of the can end, part rotation is imparted to the turret 12 to move the lined can end from the assembling station, while at 115 the same time the slide block 57 starts its downward movement and through the engagement of the catches 60 with the ejector slides or rods 62 carries therewith the lined can end. However, before the lined can ends 120 have been lowered within the vertical opening 13 of the turret 12, the said turret will have advanced to such a position as to place the raised lined can end onto the deflector plate 67, interposed within the circumferential clearance space 17, between the upper surface of the turret 12 and the disk 15', and situated a slight distance beyond the assembling station—Fig. 2 of the drawings. This plate during the rotary movement of 130

the turret, raises the lined can end above the disk 15', and engaging with the fixed curved discharge walls 68, the same is deflected from the surface of the disk 15' to a suitable point of discharge.

- 6 The cutting, can end feed and assembling stations are indicated respectively in Figs. 1 and 2 of the drawings by the reference letters C, C' and C², and it will be understood that in the operation of the machine the ring liner is cut from the fibrous web or blank at the station C, after which the cut ring liner is carried by the composite cutting die through the intermittent rotation 10 of the turret 12 to the can end feed station C', at which station a can end is positioned relative to the cut ring liner. The cut ring liner with the positioned can end is then advanced or conveyed by the intermittent 15 rotation of the turret 12 to the assembling station C², at which station the cut ring liner is moved from between the cutting members of the composite cutting die and placed onto the flange of the can end, after 20 which assembling operation the lined can end is discharged from the machine.

- I am fully aware that changes may be made in the details of construction of the working parts of the described apparatus 25 without creating a departure from the spirit of the invention, and I wish to be understood as claiming broadly the inter-connected working instrumentalities for the cutting of the ring liner from a web or blank on a single movement of the die punch (whatever the construction thereof may be), co-acting with a composite cutting die, the carrying of the cut ring liner within the composite die to a can end feed station for 30 having a can end positioned relative to the cut ring liner, and transferring the cut ring liner so held within the composite die and a positioned can end to an assembling station where the cut ring liner is applied to 35 the flange of the can end.

Having thus described the invention what is claimed as new and desired to be protected by Letters Patent is:—

1. A machine for the described purpose, 40 the same comprising a horizontally rotatable turret provided with a plurality of circumferential vertically disposed openings, a composite cutting die secured within each of said openings, reciprocating means co-acting 45 with said composite die for the cutting of a ring liner of less diameter than a can end from a web or blank positioned between the said means and the composite cutting die and leaving the same within the said die, 50 can end feed devices for positioning a can end with respect to the cut ring liner carried by the composite cutting die, assembling means for removing the cut ring liner from within the composite cutting die and applying the same to the flange of the positioned 55

can end, and mechanism for imparting rotation to the turret for carrying the composite cutting die with the cut liner ring therein from the cutting station to a can end feed station and from the said can end feed station with a positioned can end to an assembling station for having the cut ring liner applied to the flange of the said can end. 70

2. A machine for the described purpose, 75 the same comprising a horizontally rotatable member provided with a series of circumferential vertically disposed openings or orifices, a composite cutting die consisting of concentric spaced cutting members situated within 80 each of said orifices, a reciprocating member co-acting successively with the composite cutting dies carried by the rotatable member when in axial alinement therewith for the cutting of a ring liner of less diameter 85 than a can end from a web or blank positioned between the composite cutting die and said member and leaving the same within the composite cutting die, mechanism for imparting step rotation to the rotatable 90 member for positioning each of the composite cutting dies with its cut ring liner successively to feeding means for positioning a can end in axial alinement with the cut ring liner, assembling means for placing 95 the said ring liner onto the flange of a positioned can end, ejecting means associated with each composite cutting die for removing the cut ring liner therefrom and applying the same to the flange of a positioned 100 can end, and devices for discharging the lined can end.

3. A machine for the described purpose, 105 the same comprising a horizontally movable member provided with a plurality of composite cutting dies, a reciprocating member co-acting successively with said dies when in axial alinement therewith for the cutting of a ring liner of less diameter than a can end from a positioned web or blank interposed 110 between the said member and die and leaving the same within the composite die, means for actuating the horizontally disposed member for conveying the said composite die with its ring liner successively to a can 115 end feed station where a can end is positioned relative to the cut ring liner and to an assembling station for having the cut ring liner applied to the flange of said can end, and devices actuated during the rest 120 periods of the horizontal movable structure for positioning a can end relative to the cut ring liner and removing the cut ring liner from the composite cutting die and applying the same to the flange of the said can 125 end.

4. A machine for the described purpose, 130 the same comprising a horizontally disposed rotatable member provided with a plurality of vertically disposed openings, a composite

- 6 cutting die in each of said openings, a reciprocating member co-acting successively with said dies for cutting from a positioned web a ring liner of less diameter than a can end 5 and leaving the same within the composite die, mechanism for imparting step rotation to the said rotatable member, devices for positioning during one step of said member a can end in axial alinement relative to the 10 cut ring liner while held within the composite cutting die, and means at a subsequent step of said rotatable member for removing the cut ring liner from the composite cutting die and applying the same to the flange of the positioned can end.
- 15 5. In a machine for the described purpose, the combination with a horizontally movable member, of a composite cutting die carried thereby consisting of two spaced cutting instrumentalities, a reciprocating member co-acting therewith for the cutting on a single stroke from a positioned web or blank a ring liner of less diameter than a can end and leaving the same within the composite 20 die, devices for positioning a can end in axial alinement with the cut ring liner while seated within the cutting die, reciprocating means for forcing the ring liner from off of the cutting die and onto the flange of the 25 positioned can end, and devices for ejecting the lined can end.
- 30 6. In a machine for the described purpose, the combination with a composite cutting die consisting of spaced cutting instrumentalities, of a reciprocating member co-acting therewith for the cutting on a single stroke thereof from a positioned web or blank a ring liner of less diameter than a can end and leaving the same within the composite 35 cutting die, of means for positioning a can end to be lined in axial alinement with the cut ring liner while held within the composite cutting die, and devices for removing the cut ring liner from within the composite die and applying the same to the flange of the positioned can end.
- 40 7. In an apparatus for the described purpose, the combination with a horizontally movable member provided with a plurality 45 of vertical openings, of a composite cutting die secured within each of said openings, a reciprocating member co-acting successively with said composite dies for the cutting of a ring liner of less diameter than a can end from a positioned web or blank on a single stroke thereof and leaving the cut ring liner within said die, mechanism for actuating the horizontally movable member for carrying the composite dies with the 50 cut ring liner thereon successively to a can end feed station and a can end assembling station, means located at said stations respectively for positioning a can end in axial alinement with the cut ring liner of a composite cutting die and for removing the ring 55

liner from said die and applying the same to the flange of a positioned can end, and devices for discharging the lined can end from the machine.

8. In an apparatus for the described purpose, the combination with a horizontally rotatable carrying member, of a plurality of composite cutting dies thereon, and each composed of spaced cutting instrumentalities, a reciprocating member coacting successively with said composite dies for the cutting from a positioned web or blank a ring liner of less diameter than a can end and leaving the same within the composite die, mechanism for actuating the carrying member for the placing of a composite cutting die with the cut ring liner therein successively within the sphere of a can end feed station and an assembling station, devices situated at the feed station for placing a can end in axial alinement with the cut ring liner carried by a cutting die, means at the assembling station operating to cause the removal of the cut ring liner from the cutting die and applying the same to the flange of the positioned can end, and devices for discharging the lined can end from the machine.

9. In a machine for the described purpose, the combination with a horizontally rotatable carrying member, of a plurality of composite cutting dies thereon, each consisting of spaced cutting instrumentalities, a reciprocating member co-acting with said dies for cutting on a single stroke from a web a ring liner of less diameter than a can end and leaving the same within the cutting die, devices for feeding a fibrous web between the said member and the composite dies, devices for feeding can ends into position relative to the cut ring liner, assembling means for removing the cut ring liner from the composite cutting die and applying the same to the flange of the positioned can end, and associated inter-working instrumentalities for actuating said mentioned parts in timed relation to each other.

10. In a machine for the described purpose, the combination with a horizontally rotatable member provided with a plurality of composite cutting dies, each comprising spaced cutting instrumentalities, of a reciprocating member co-active therewith for the cutting on a single stroke thereof from a positioned web or blank a ring liner of less diameter than a can end and leaving the same deposited within a composite die, can end feed means for delivering and positioning a can end in axial alinement relative to the cut ring liner while on the composite cutting die, an ejector carried by each of said composite dies carried by the horizontally rotatable member, means for advancing a web between the cutting members, inter-connected instrumentalities for actuat-

- ing respectively in timed relation the reciprocating member co-acting with the composite dies, imparting step movement to the web, actuating the can end feed means and 5 the ejector of the composite dies, and imparting step movement to the mentioned horizontally rotatable member.
11. In a machine for the described purpose, the combination with a composite cutting die consisting of spaced cutting instrumentalities, of a reciprocating cutting member co-acting with said die for the cutting from a web a ring liner of less diameter than a can end, and leaving the same within the 15 die, means for feeding a web between said members, can end feed mechanism for delivering and positioning a can end, assembling devices for moving the cut ring liner from within the composite die and applying the same to the flange of a positioned can end, and mechanism for carrying the composite cutting die with its cut ring liner by a step movement from position in axial alinement with its co-acting cutting member to the can end feed devices and the 25 assembling devices respectively, and restoring the same to axial alinement with its co-acting cutting member.
12. In an apparatus for the described purpose, the combination with a composite cutting die consisting of spaced cutting members, a reciprocating die member co-acting therewith for the cutting on a single stroke thereof from a positioned fibrous web or 30 blank a ring liner and leaving the same deposited on the composite cutting die, means for positioning a can end in axial alinement with said ring liner, assembling means for removing the cut ring liner from the composite cutting die and applying the same to the flange of the positioned can end, mechanism for successively conveying the composite cutting die with its ring liner to the means for positioning a can end in axial 35 alinement with the cut ring liner and to the assembling means for applying the ring liner to the flange of the positioned can end, and devices for discharging the lined can end.
- 40 13. In an apparatus for the described purpose, the combination with a composite cutting die consisting of two concentric spaced cutting members, of reciprocating means co-acting therewith for cutting from a fibrous blank a ring liner and leaving the same on 45 the composite cutting die, means for positioning a can end in axial alinement with a ring liner while maintained on the cutting die, and devices for removing the cut ring liner and applying the same to the flange of the positioned can end.
14. In an apparatus for the described purpose, the combination with a composite cutting die consisting of two concentric spaced cutting members, of reciprocating means co-acting therewith for cutting from a fibrous blank a ring liner and leaving the same on 55 the composite cutting die, an ejector device working between the spaced cutting members of the cutting die, means for positioning a can end in axial alinement with a ring liner while maintained on the cutting die, and devices for actuating the ejector device for removing the cut ring liner and applying the same to the flange of the positioned can end.
15. In an apparatus for the described purpose, the combination with a horizontally rotatable carrier, of a plurality of composite cutting dies carried thereby, each consisting of concentrically disposed cutting members, a reciprocating cutting member co-acting successively with the composite cutting die for cutting a ring liner from a positioned fibrous blank and leaving the same on the said die, a reciprocating ejector device associated with each composite cutting die, means for positioning a can end in axial alinement with a cut ring liner while on the cutting die, and devices for actuating the ejector device for removing a cut ring liner from the composite cutting die and applying the same to the flange of a can end while in its positioned axial alinement therewith.

In testimony whereof I have signed my name to this specification in the presence of two subscribing witnesses.

AXEL JOHNSON.
